UNITED STATES PATENT AND TRADEMARK OFFICE
CERTIFICATE OF CORRECTION

PATENT NO. : D657,834 S
APPLICATION NO. : 29/409301
DATED : April 17, 2012
INVENTOR(S) : Andrew G. V. Oldknow et al.

Page 1 of 1

It is certified that error appears in the above-identified patent and that said Letters Patent is hereby corrected as shown below:

On the cover page, item (57) under "Description,"

"The broken line showing of various elements within the shaded are for environmental purposes only and form no part of the claimed design."

has been replaced with

--The broken line showing of various elements within the shaded area is for environmental purposes only and forms no part of the claimed design.--

Signed and Sealed this
Thirteenth Day of November, 2012
